UNITED STATES PATENT OFFICE.

ARTHUR C. ROWLEY, OF PHILADELPHIA, PENNSYLVANIA, ASSIGNOR TO GLOBE AUTOMATIC SPRINKLER COMPANY, OF PHILADELPHIA, PENNSYLVANIA, A CORPORATION OF PENNSYLVANIA.

ALARM MECHANISM.

Application filed October 30, 1923. Serial No. 671,775.

This invention relates to apparatus for controlling the flow of water from a fire extinguishing system to an alarm mechanism and has as one of its objects the provision of 5 a relatively simple and substantial device which upon opening of a main alarm valve shall cause or permit such a flow of water to the alarm apparatus as will maintain a constant alarm with a relatively small 10 charge of water from the system.

A further object of the invention is to provide a novel construction and arrangement of alarm mechanism wherein the water for operating the alarm device or apparatus 15 shall be taken from the sprinkler- or delivery-side of an alarm valve with the advantage that under operating conditions the mechanism has an effect upon the system similar to that caused by or due to the opening 20 of an additional sprinkler head.

Another object of the invention is to provide an alarm mechanism in which the valve controlling the flow of water to the alarm apparatus will close only when the pressure 25 in the receiving chamber has fallen to zero, and in which the arrangement is such that under conditions of operation there shall be no chattering or vibratory action of the valve controlling the flow of water to the alarm 30 apparatus.

I also desire to provide mechanism of the above noted class which shall be of such a nature as to be incapable of causing intermittent alarms although it shall insure a constant alarm with a relatively small amount 35 of water escaping or delivered from the system.

These objects and other advantageous ends I attain as hereinafter set forth, reference 40 being had to the accompanying drawings, in which,

Fig. 1 is an elevation partly in vertical section and to some extent diagrammatic, illustrating an alarm mechanism arranged 45 in accordance with my invention;

Fig. 2 is a vertical section on the line 2—2, Fig. 1 on an enlarged scale, illustrating the detail construction of the flow controlling device constructed in accordance with my invention; and,

Fig. 3 is an elevation partly in vertical section on the line 3—3, Fig. 2.

In the above drawings, 1 represents an alarm valve of any suitable or desired con-

struction having an inlet 2 connected to a 55 water supply system and an outlet 3 connected to the sprinkler pipe or riser of a sprinkler system. Within and forming part of this valve is a clapper 4 normally closed to cut off communication between its inlet and outlet and having connected to or formed as part of it, an arm 5 carrying an auxiliary clapper 6. The latter is designed to normally close an inlet from the upper part of the alarm valve to a conduit 7 and the arrangement 60 is such that said auxiliary valve maintains said inlet closed as long as the main clapper 4 remains seated. Unseating of said main clapper 4 likewise causes unseating of the auxiliary clapper 6 and permits flow of 65 water into the conduit 7. Said conduit, in accordance with my invention, is connected to a flow controlling device which includes a chamber 8 whose otherwise open lower side or bottom is closed by a diaphragm 9. The 70 upper part of this chamber includes a partition 10 forming a relatively small receiving chamber 11 into which the conduit 7 is directly connected. This partition has through it a passage in which is mounted a relatively 75 restricted nozzle- or orifice-member 12, coaxial with which is a screen 13 held in place by a removable plug 14 threaded into the side of the casing. The arrangement is such 80 that water passing from conduit 7 through the receiving chamber 11 to the nozzle 12 is necessarily compelled to pass through the screen so that foreign matter which might otherwise clog said nozzle is effectually excluded.

The diaphragm 9 is clamped against the flanged lower face of the chamber 8 by a ring 15 held in place by suitable bolts and the lower face of said ring has a second diaphragm 16 clamped against it by the flanged edge of a second chamber 17. This latter is clamped to the ring in any suitable manner as by bolts and has connected to its side a conduit 18 leading from the upper or delivery side of the alarm valve 1. This conduit 100 is preferably connected to said second chamber through a fitting 19 having a restricted passage therethrough and this chamber has leading from it a conduit 20 for conveying water to any desired form of mechanical or electrical alarm apparatus. The inlet to said conduit is through the valve seat 21, normally closed by a valve 22 fulcrumed to a

fixed portion of the casing by a pin 23 and having a projecting arm 24. Said valve is preferably made in the form of a sleeve-like structure inwardly flanged at its lower end 5 and having a plug 25 threaded into its upper end. The latter has a central, downwardly projecting portion designed to engage a piston-like element 26 slidably mounted in said sleeve structure and confined therein by the 10 flange thereof. Said element has a flat lower face designed to engage and normally close the opening into the seat structure 21. This piston-like valve element 26 is slidably mounted in its supporting structure and is 15 designed to make a liquid-tight fit with the seat 21, there being a passage 27 through the plug 25 whereby water under pressure is admitted to the upper face of said valve element. Between the two diaphragms 9 and 20 20 is mounted a flanged spacer 28 through which extends a bolt-like member 29 having a post 30 projecting from its lower end in such position as to engage the arm 24 when the valve 22 is closed and the dia- 25 phragms are in their upwardly bowed or normal positions. The diaphragm 9 has in it a relatively small hole 31 designed to drain water out of the chamber 8 into the space between the diaphragms and this space through 30 a passage 32 is connected to a waste pipe 33 allowing free escape of any water entering said space.

Under normal conditions when the alarm valve 1 is closed, water fills the conduit 18 35 and also the chamber 17. The chamber 8, however, is empty, since the auxiliary clapper 6 normally cuts off water from conduit 7. Upon opening of one or more of the 40 sprinklers of the fire extinguishing system connected to the outlet 3 of the alarm valve, there is a flow of water through said valve which causes opening of the main clapper 4. This at once causes opening of the auxiliary clapper 6 and permits flow of water 45 through the conduit 7 to the receiving chamber 11 and to the chamber 8. When under the conditions noted, water enters said chamber 8 more quickly than it can drain out through the hole 31 (as is the case when the clapper 4 is open), it fills said chamber within a definite time after the sprinkler 50 has opened and ultimately exerts on the diaphragm 9 sufficient pressure to overcome the upward pressure exerted upon the dia- 55 phragm 16 by the water in the chamber 17. Said two diaphragms thereupon move downwardly, causing the post 30 to act on the arm 24 and open valve 22. Water is now free to flow from the delivery side of the 60 alarm valve through the conduit 18 into the chamber 17 and thence through the conduit 20 to the alarm apparatus which will thereby be operated. It is obvious that this flow 65 will continue as long as the main clapper 4 remains open and hence as long as there is

a flow from one or more of the sprinklers of the system connected to said valve. The alarm caused by such continued delivery of water through the pipe 20, is therefore continuous and it is to be noted that such flow 70 has the same bleeding effect upon the system as would the opening of an additional sprinkler head. Upon cessation of flow through the alarm valve, the main clapper 4 as well as the auxiliary clapper 6 will 75 automatically return to their seated positions, so that flow of water through the conduit 7 to the chamber 8 is cut off. As a consequence, the water in said chamber quickly escapes through the opening 31 into 80 the drain pipe 33, whereupon the pressure of water in the chamber 17 causes the dia- phragms 9 and 16 to be moved upwardly and permits closure of the valve 22, with a 85 consequent stoppage of the water flow to the alarm apparatus. Obviously, if the opening of the main clapper 4 is intermit- 90 tent or of merely a temporary nature, the water delivered to the chamber 8 by the resultant opening of the auxiliary valve 6 95 drains away through the hole 31 before it can accumulate above the diaphragm in sufficient quantity to cause opening of the valve 22. The device, therefore, is not like- 100 ly to cause operation of the alarm apparatus except when one or more sprinkler heads has opened.

As shown in Fig. 3, I preferably provide the chamber 17 with an opening normally closed by a plate or cover 35 through which 100 access may be had to the valve 22 and post 30. Said post is preferably threaded into the bolt-like member 29 so as to be conveniently adjustable, to permit closure of the valve 22 when the diaphragms are in 105 their upper positions.

I claim:

1. The combination of a flow controlling device comprising two chambers having a movable wall between them; a valve actuated by movement of said wall for controlling flow from one of the chambers to an alarm device; an alarm valve; a conduit connecting said chamber with the delivery side of said alarm valve; and a conduit from 110 the other chamber having its inlet controlled by the clapper of the alarm valve.

2. The combination of an alarm valve in- 115 cluding a main clapper and an auxiliary valve movable with the said clapper; a flow controlling device comprising a chamber in free communication with the delivery side of the alarm valve; a valve controlling flow of liquid from said chamber; a conduit through which the flow is controlled by said auxiliary valve; and means actuated by fluid 120 from said conduit for operating the flow- 125 controlling valve.

3. The combination of an alarm valve in- 130 cluding an auxiliary valve movable with

the clapper thereof and a flow-controlling device comprising a casing having two main chambers and an auxiliary chamber connected through a restricted orifice to one of said chambers; a conduit normally closed by the auxiliary valve and connected to deliver water to the auxiliary chamber of said casing; at least one diaphragm between the main chambers of the casing; a conduit connecting the second of the main chambers with the delivery side of the alarm valve; with a normally closed valve controlling flow from said second chamber and governed by the diaphragm.

4. The combination of an alarm valve including a main clapper and an auxiliary valve movable with said clapper; a flow controlling device comprising a chamber having a discharge port and a relatively small inlet port; a duct placing said inlet port in free communication with the delivery side of the alarm valve; a discharge valve controlling the discharge port; a conduit through which the flow is controlled by said auxiliary valve and means actuated by fluid from said conduit for operating the said discharge valve.

ARTHUR C. ROWLEY.
